P.C.; Jason Plotkin(57) **CLAIM**

The ornamental design for a cut diamond, as shown and described.

DESCRIPTION

FIG. 1 is a perspective view of the cut diamond;
FIG. 2 is a top plan view of the cut diamond;
FIG. 3 is a side elevation view of the cut diamond;
FIG. 4 is a bottom plan view of the cut diamond;
FIG. 5 is a top plan view of the cut diamond in a setting; and,
FIG. 6 is a front elevation view of the cut diamond shown
in a setting.
The broken lines shown in the drawings illustrate environmental
structure and form no part of the claimed design.
